C. A. HULTQUIST

DRILL STEEL RETAINING DEVICE

Filed Jan. 12, 1927

INVENTOR.
CHARLES A. HULTQUIST
BY *A.B. Bowman*
ATTORNEY

UNITED STATES PATENT OFFICE.

CHARLES A. HULTQUIST, OF LOS ANGELES, CALIFORNIA.

DRILL-STEEL-RETAINING DEVICE.

Application filed January 12, 1927. Serial No. 160,642.

This invention relates to a device for preventing the drill steel of drilling machines from becoming detached from the means of the machine in which it is loosely seated.

The principal object of this invention is to provide improvements over my copending application for drill-steel retaining devices, filed on even date herewith.

The objects of my improvements are: first, to provide a generally U-shaped drill-steel retaining device which is provided at its intermediate, or connecting portion with a transversely slotted abutment adapted to be engaged by an abutment on the drill steel 10 of the drilling machine, the legs of the device being forked and provided with bearings at the inner ends of the forked portions and with slidable bearings mounted on the furcations of the forked portions, the 15 slidable bearings of each leg being retained against the pivot means of the machine by pairs of light compression springs mounted over the furcations of the forked portions, said springs being made as resilient and as 20 light as possible to reduce to a minimum crystallization of the spring means which often takes place when single, heavier springs are used; and, second, to provide, as a 25 whole, a novelly constructed drill-steel retaining device and one which is simple and economical of construction, durable, efficient, practical and which will not readily deteriorate or get out of order.

With these and other objects in view as 30 will appear hereinafter, my invention consists of certain novel features of construction, combination and arrangement of parts and portions, as will be hereinafter described in detail and particularly set forth 35 in the appended claims, reference being had to the accompanying drawings and to the characters of reference thereon which form a part of this application in which:

Figure 1 is a side elevation view of a 40 conventional drilling machine with my drill-steel retaining device mounted thereon and shown in a steel retaining position thereon, a drill steel being shown in the barrel of the machine; and, Fig. 2 is an enlarged fragmentary side elevational view thereof taken at 2-2 of Fig. 1, showing particularly my 45 drill-steel retaining device and showing also my device by dotted lines in an angular or out-of-the-way position for removing the 50 drill steel.

Like characters of reference refer to similar parts and portions throughout the views of the drawings.

The drilling machine, indicated by the character 1 in the drawings, may be of any 60 suitable construction or type of reciprocating drilling machine. The drilling machine is provided, in conventional construction, at its lower end with a barrel 2 in which is inserted the one end of a drill steel 3 which is provided with a shoulder, or abutment, 4 from the end of the drill steel inserted in the barrel. The drill steel is permitted to slide readily in and out of the barrel 2, when the retaining device, to be described 70 hereinafter, is not in such position as to prevent such movement of the drill steel.

The retainer, or retaining device, indicated by R in the drawings, is generally U-shaped and pivoted with its legs, indicated by 6, at 75 the opposite sides of the barrel 2. At the cross, or connecting portion of the arms or legs 6 of the U-shaped retainer, is a transversely slotted, or a transversely extending semi-circular, or U-shaped, abutment 5. Said abutment 5 partly surrounds the drill steel when the retainer is in a downward or retaining position, and is adapted to be engaged by the outer face of the abutment of the drill steel, during the drilling operation, to retain the drill steel in the barrel. The ends of the legs of the semi-circular, or U-shaped abutment 5 are provided with upwardly extending lugs 5^a to absolutely prevent the retainer from being shifted out of 80 the way when the drill steel is inserted into the barrel with its shoulder, or abutment, 4 against the abutment 5.

The legs 6 are enlarged transversely and laterally intermediate their ends and are 85 bifurcated, or forked, at said enlarged portions; the furcations extending toward the ends of the legs and parallel to each other and to the general direction thereof. The planes extending through the furcations of each leg are perpendicular to the plane extending through the two legs 6. The inner ends of the bifurcated portions, or forks, of said legs provide semi-circular bearings 6^a which are positioned against and around the 90 undersides of studs 7 projecting laterally from the sides of the barrel 2 and in alignment with the axis of the barrel. The barrel 2 is provided at its opposite sides with 95 bosses 2^a adjacent and around the studs 7, 100

110

the outer faces of said bosses being engaged by the adjacent sides of the enlarged portions of the legs 6 for positioning the retainer against lateral movement. The furcations, indicated by 6^b, of the retainer are in the form of bolts and serve as guides. On the furcations of each leg is slidably mounted a bearing plate 8 which is normally positioned against the upper side of the stud 7 in opposed relation to the bearing portion 6^a. At the outer ends of the furcations of each leg is adjustably mounted a spring retaining plate 9 which is held in position on said furcations by nuts 10 screwed on to the outer ends of the furcations. Between the plates 8 and 9, and around each of the furcations, or bolts 6^b, are positioned compression springs 11. These springs are relatively light so as to reduce crystallization of the springs to a minimum. The use of two springs 11 on each of the furcations provides balancing of the force against the slideable bearing 8 and avoids binding of the same on said furcations. At the upper sides of the spring retaining plates 9, around the portions through which the furcations extend, are provided upwardly extending rounded lugs, or ridges 9^a which radiate outwardly from the holes therein. Said lugs, or ridges are adapted to extend into correspondingly shaped radial slots 10^a at the inner sides of the nuts 10 to lock said nuts against unscrewing.

The upper side of one, or both, of the studs 7, is provided with longitudinal, substantially semi-circular depression 7^a into which extends, when the retainer is in a steel retaining position, a correspondingly shaped projection, or ear, 8^b which extends downwardly from the middle portion of a circular depression 8^c into which the upper side of the pivot portion, or stud, 7 normally extends. Thus, the retainer, or retaining device, is locked relative to the pivot means by the interlocking means of the studs 7 and the plates 8 against movement, unless considerable force is brought to bear against the lower end of the retainer, and only when the abutment 4 is clear of the lugs 5^a.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. The combination with the barrel of a drilling machine, and a drill steel in the barrel, of a pivot means extending to the side of said barrel, a drill-steel retainer having

a portion at the end of said barrel engageable by an abutment on said drill steel and having means extending to the side of said barrel, said means having a bifurcated portion straddling said pivot means and having a bearing at the inner end of said bifurcated portion engaging the underside of the pivot means, a bearing member slidably mounted on the furcations of the bifurcated portion and engaging the upper side of said pivot means, said bearing member and pivot means having portions adapted to hold the retainer in a drill-steel retaining position, nuts at the ends of said furcations, and compression springs mounted around each of said furcations and positioned between said bearing member and said nuts.

2. The combination with the barrel of a drilling machine, and a drill steel in the barrel, of a pivot means extending to the side of said barrel, a drill-steel retainer having a portion at the end of said barrel engageable by an abutment on said drill steel and having means extending to the side of said barrel, said means having a bifurcated portion straddling said pivot means and having a bearing at the inner end of said bifurcated portion engaging the underside of the pivot means, a bearing member slidably mounted on the furcations of the bifurcated portion and engaging the upper side of said pivot means, said bearing member and pivot means having portions adapted to hold the retainer in a drill-steel retaining position, a spring retaining plate slidably mounted on and between said furcations, nuts at the outer ends of said furcations for holding said spring retaining plate in position thereon, and compression springs mounted around each of said furcations between said bearing member and said spring retaining plate.

3. The combination with a barrel of a drilling machine, and a drill steel in the barrel, of studs projecting laterally from the barrel in alignment therewith, a U-shaped drill-steel retainer, the legs thereof having forked portions forming, at their inner ends, bearings engaging the under sides of the studs, the connecting portion of the legs of the U-shaped member being engageable by an abutment on said drill steel, bearings slidably mounted at their opposite ends on the furcations of each leg, said bearings and said studs having portions adapted to interlock with each other and hold the retainer in a drill-steel retaining position, spring retaining plates slidably mounted on and between the furcations of each leg, nuts at the outer ends of said furcations for holding said spring retaining plates in position, and compression springs positioned around each of said furcations with their ends between the end portions and adjacent sides of said bearings and said plates.

4. The combination with the barrel of a

drilling machine, and a drill-steel in the barrel, of studs projecting laterally from the barrel in alignment therewith, a U-shaped drill-steel retainer, the legs thereof being
5 considerably enlarged intermediate their ends and provided with forked portions extending from the enlarged portions toward the ends of the legs, the legs of the retainer forming at the inner ends of the forked portions and at the enlarged portions thereof bearings engaging the under sides of the studs and bosses at both sides of the barrel around said studs, the connecting portion of the legs of the U-shaped retainer
10 being engageable by an abutment on said drill steel, bearings slidably mounted on the furcations of said forked portions, said bear-

ings and said studs having portions adapted to interlock with each other to hold the retainer in a drill-steel retaining position, 20 spring retaining plates slidably mounted at their opposite end on and between the furcations of each leg, nuts at the outer ends of said furcations for holding said spring retaining plates in position, and compression 25 springs positioned around each of said furcations with their ends bearing against the adjacent sides of said slideable bearings and said spring retaining plates.

In testimony whereof, I have hereunto set 30 my hand at Los Angeles, California this 3rd day of January 1927.

CHARLES A. HULTQUIST.
